UNITED STATES PATENT OFFICE

AUGUSTUS C. DURDIN, JR., OF CHICAGO, ILLINOIS

VACUUM CONDENSATION PUMP

Application filed January 21, 1930. Serial No. 422,434.

This invention relates to vacuum condensation pumps, and its principal object is the provision of a novel arrangement and combination of elements for separating air and other gases from water or other liquids and pumping the liquid to a boiler or other place. The present invention has been designed particularly for use in connection with steam heating plants, although its use is not limited thereto, and it is arranged to be connected with the returns of the plant and operates to separate the air and other gases from the water of condensation and return the water back to the boiler.

One object is to provide novel means whereby little or any of the water is lost from the system. Apparatus of this character usually employs a rotary pump for creating a partial vacuum in the system and a centrifugal water pump for pumping the water back to the boiler, and one of the objects of the present invention is to provide a novel combination of elements whereby the vacuum pump may continuously operate at its maximum efficiency.

Another object is to provide a novel arrangement of parts in combination with a receiver for the water of condensation and other gases, whereby a partial vacuum is created in a vacuum chamber and the water, air or gases are moved from the receiver into the vacuum chamber, the air and other gases discharged from said chamber to the atmosphere and the water is pumped from said chamber back to the boiler or to other desirable places. Another object is to move the same or substantially the same amount of water into the vacuum chamber as the water pump is capable of handling.

With these and other objects and advantages in view, this invention consists in a vacuum condensation pump embodying a rotary vacuum pump having its intake end opening into the vacuum chamber and adapted to create a partial vacuum in said vacuum chamber, whereby water, air and other gases are caused to flow into the vacuum chamber, from which the water freed from the air and other gas, is pumped by a centrifugal water pump back to the boiler or any other de-

sirable place. It further consists in a vacuum condensation pump, as above set forth, having means for regulating the flow of water from the receiver to the vacuum chamber, whereby a predetermined maximum volume of water may flow through said vacuum chamber which is capable of being handled by the centrifugal water pump.

It further consists in a vacuum condensation pump in which both air and water flowing from the receiver are moved into a vacuum chamber by a rotary vacuum pump and the water freed of the air is pumped back to the boiler or other desired place by the water pump.

It further consists in the several novel features of construction, arrangement and combination of parts hereinafter fully set forth and claimed.

The invention is clearly illustrated in the drawings accompanying this specification in which—

Figure 1 is a view partly in front elevation and partly in vertical longitudinal section of a vacuum condensation pump embodying the preferred form of the present invention, the section being taken on the broken line 1—1 in Fig. 2;

Fig. 2 is a vertical cross section taken on the line 2—2 of Fig. 1;

Fig. 3 is a horizontal section taken on the broken line 3—3 of Fig. 1;

Fig. 4 is a horizontal section taken on the broken line 4—4 of Fig. 1;

Fig. 5 is a vertical cross section taken on the broken line 5—5 of Fig. 1; and

Fig. 6 is a view partly in side elevation and partly in vertical longitudinal section illustrating a modified form of the invention.

The above drawings are not working drawings, but are rather schematic and are intended principally for the purpose of illustrating embodiments of the present invention.

Referring to said drawings, and first to Figs. 1 to 5, inclusive, the reference character 10 designates a receiver which may be connected with the returns 11 of a steam heating plant. As is well understood, water of condensation, air and other gases enter the receiver, where the air and other gases collect

adjacent the top of the receiver while the water collects below the air and other gases.

Mounted upon the receiver 10 is the pump structure, illustrated generally at 12, which in the preferred form, has a chambered casing 13 in which is a pump shaft 14 journaled in suitable bearing brackets 15 located adjacent the lower end of the casing. The pump shaft is arranged to be coupled to an electric motor (not shown) or driven from any other suitable source of power. The pump casing 13 is usually formed of an upper and lower section bolted together along a horizontal plane co-incident with the axis of the pump shaft 14.

Within the pump casing 13 and formed integral therewith is the casing 16^a of a rotary vacuum pump 16 which, in the preferred form, employs throwing water in its operation. The impeller 17 of the vacuum pump is of well known construction and is mounted upon the pump shaft 14. The throwing water inlet 18 for the water pump 16 opens from a water inlet passage 19 formed by a wall 20, preferably cast as a part of the pump casing 13, and having an inlet opening at its lower side which communicates with a water reservoir 21 partially surrounding the vacuum pump and separated from the remainder of the interior of the pump casing 13 by a top wall 22 and a cross wall or partition 23. The cross wall or partition 23 may form one side wall of the vacuum pump 16.

An air inlet 25 through which the air passes to the vacuum pump is located adjacent the upper end of the pump casing 13 and is formed in a short horizontal wall 24 which defines part of an air passageway 26 which leads from the air inlet 25 to the air inlet openings 27 of the vacuum pump. The air passageway 26 is formed in part by an outside wall of the pump casing 13 and by other upright walls 28 formed integral with said outside wall. The air passage 26 is enlarged at its lower end, as is seen in Fig. 5, and the enlarged part is separated from the passageway which leads from the water inlet chamber to the impeller 17 of the vacuum pump by an annular partition member 29 having alternately arranged openings therein for the passage of water and air to the impeller, as is customary, check valve 25^a controls port 25.

In the operation of a vacuum pump of the water throwing type shown, water is admitted through the alternately arranged water inlet openings in the partition 29 and passes through the spaces between the vanes or blades of the impeller where the slugs of water are thrown outward by the centrifugal action of the pump and air is drawn in through the air inlet openings in the partition and enters the spaces between the water slugs and is carried out by the slugs of water, the water and air discharging into the water

reservoir 21. The throwing water returns to the vacuum pump and is used over and over again, while the air which discharges from the vacuum pump passes out through an air discharge opening, as will be presently described.

Extending upward from the top wall 22 of the water reservoir 21 is an air passageway 30 which opens from the interior of the water reservoir 21 and leads upward through the top wall 31 of the pump casing 13, where the passageway 30 opens to the atmosphere or may connect with an air discharge pipe 32 leading upward for a considerable distance above the pump structure. A strainer 33 is sometimes provided at the top of the air discharge passageway 30 and serves to catch any foreign matter which may be introduced through the pipe 32 in case the apparatus is primed by introducing water through the pipe 32. It is preferred to place an outwardly opening check valve (not shown) at some point in the air discharge pipe 32.

The cross wall or partition 23 may form one wall of the casing 34 of a centrifugal water pump 36 in which is contained an impeller 35 mounted upon the pump shaft 14. The water pump 36 operates to discharge water freed from air through a discharge pipe 37 back to the boiler or any other desired place. An outwardly opening check valve 38 is usually interposed in the discharge pipe 37.

Between the top wall 22 of the water reservoir 21 and the top wall 31 of the pump casing is a chamber 39 which serves as a vacuum chamber into which water, air and other gases are moved from the receiver 10 by the partial vacuum caused by the vacuum pump 16. A water leg or water passageway 40 extends down from the chamber 39 between an outer wall of the pump casing 13 and the pump casing 34 of the water pump 36 and communicates with the inlet 41 of the impeller 35 of the water pump.

Extending from a point adjacent the bottom of the receiver 10 is a conduit or pipe 42 which is connected to the pump casing 13 and opens into the interior of the vacuum chamber 39 through a port 43. In the operation of the apparatus, the conduit or pipe 42 serves to convey water or other liquid from the receiver 10 to the vacuum chamber 39. Extending from a point adjacent the upper end of the receiver 10 is a second conduit or pipe 44 which is connected to the pump casing 13 and opens into the interior of the vacuum chamber 39 through a port 45 which is located considerably above the port 43. In the operation of the apparatus, the conduit or pipe 44 serves to convey air or other gases from the upper end of the receiver to the vacuum chamber 39.

The port 45 between the air conduit 44 and vacuum chamber 39 is controlled by a float

130

valve 46 carried by a float rod 47 fulcrumed upon the pump casing 13 and having a ball float 48 upon its free end. The float valve 46 serves to close the port 45 to the air conduit whenever the water in the vacuum chamber reaches a low level and it gradually opens the port 45 as the level of the water rises in said vacuum chamber. The purpose of this valve mechanism is to control the flow of water from the receiver to the vacuum chamber 39, so that the water pump may discharge it from the vacuum chamber as fast as it flows into the same.

When the valve 46 is closed, the entire force of the vacuum is applied to the column of water passing through the water conduit 42, and when the valve is opened somewhat, due to the rise of the water in the vacuum chamber, air is drawn into the vacuum chamber through the air conduit 44, and, consequently, the force of the vacuum is lessened upon the column of water in the water conduit 42. The parts are so proportioned and designed that the float valve is opened sufficiently (due to the rise of water in the vacuum chamber to a predetermined level) that the water is caused to flow into the vacuum chamber 39 at the same rate as the water pump discharges the water from the vacuum chamber.

To guard against an abnormal condition arising in which water might enter the vacuum chamber faster than the water pump could discharge it, an air inlet 49 is provided in the top wall of the vacuum chamber 39, which inlet is closed by a float valve 50 connected to the float rod 47 by a link 51 having a lost motion connection between said float rod, whereby the latter may move upward and thereby open the float valve 46 to a certain degree before the float opens the float valve 50. In case the water in the vacuum chamber 39 rises above a predetermined level, the float 48 opens the float valve 50, thereby opening the vacuum chamber 39 to the outer atmosphere, and the vacuum in said chamber being reduced, the vacuum pump becomes ineffective for moving water from the receiver to the vacuum chamber until the water pump has pumped enough water out of the vacuum chamber 39 to lower the level of the water therein sufficiently to permit the valve 50 to close, after which the vacuum pump again builds up vacuum in the vacuum chamber 39 necessary to cause the water to flow from the receiver into the vacuum chamber. Usually the float valve 50 is contained in a housing 52 at the end of which is an inwardly opening check valve 53. As a consequence, there is no danger of the water flooding the vacuum chamber and entering the air port 25 from which it would be carried to the vacuum pump and by it discharged through the air passage 30.

Inasmuch as some slight amount of water is lost from the water reservoir 21 in the

operation of the vacuum pump, a water passageway 54 is provided from the water pump 36 to the water reservoir 21 and the port between said water passageway 54 and water reservoir 21 is controlled by a float valve 55 having a ball float 56 which is raised and lowered by the water contained in the water reservoir 21. As the level of the water therein lowers, the float moves downward and opens the float valve 55, thereby admitting water from the water pump 36 to the water reservoir 21.

To guard against any leakage from the water reservoir 21 back to the water pump, an upwardly opening check valve 57 is provided in the water passageway 54. This check valve 57 permits the water to be moved through the water passageway 54 by the impeller of the water pump, but prevents any return of water to the water pump through said water passageway 54. The receiver is preferably provided with a pressure switch and a float switch, as is customary in apparatus of this character, for automatically starting and stopping the motor of the pumping apparatus.

The operation of the vacuum condensation pump above described is as follows:

The vacuum pump having been initially primed, which may be done by introducing water through the air discharge passageway 30, the motor is started. The vacuum pump exhausts the air from the vacuum chamber 39, thereby creating a partial vacuum therein which causes water in the receiver above the lower end of the water conduit 42 to flow through said conduit and into the vacuum chamber from which it is discharged by the water pump 36. As the level of the water rises in the vacuum chamber, it partially opens the float valve 46, thereby establishing communication between the vacuum chamber and the upper portion of the receiver through the air conduit 44.

As the water continues to rise in the vacuum chamber 39, the volume of air drawn into the vacuum chamber increases proportionately to the extent that the float valve 46 opens, and at a predetermined position of the float valve, the flow of water into the vacuum chamber is as great, or substantially as great, as the water pump is capable of discharging it from the vacuum chamber. The air which is exhausted from the vacuum chamber passes through the vacuum pump and is discharged into the water reservoir 21 from which the air passes through the air passage 30 and discharges to the outer atmosphere through the air discharge pipe 32. It is to be observed that the water re-enters the vacuum pump and is used again and again in conjunction with the impeller to create the suction in the vacuum chamber.

In case an abnormal condition arises in which the water flows into the vacuum cham-

ber faster than the water pump can discharge it therefrom, the water rises in the vacuum chamber, thereby finally unseating the float valve 50, whereby outside air is admitted to the vacuum chamber and the vacuum therein is reduced. When this occurs, the vacuum pump 16 becomes ineffective for moving water from the receiver to the vacuum chamber, during which interval of time the water pump discharges the surplus water from the vacuum chamber, and when the level of the water has lowered sufficiently to permit the float valve 50 to close, the vacuum pump again builds up vacuum in the vacuum chamber, thereby causing water to be moved thereinto from the receiver, as above described.

It is to be observed that under normal conditions, the level of the water in the vacuum chamber will remain substantially at a height where the float valve 46 is opened to such an extent that the flow of water to the vacuum chamber will equal or substantially equal the outflow from the vacuum chamber caused by the water pump. It is to be observed also that the vacuum extends to the air conduit 44 and to the receiver and places a vacuum on the returns of the steam heating plant.

In the modified form of the invention illustrated in Fig. 6, the mode of operation of the apparatus is substantially the same as that of the preferred form. In this modified form, the pump structure 13^a is mounted upon the receiver 10^a and contains a hydro-turbine pump 16^a and a centrifugal water pump 36^a both mounted on a pump shaft 14^a. Above the pump structure 13^a is a tank 13^b containing a vacuum chamber 39^a and a water reservoir 21^a separated by a partition 22^a. The water conduit 40^a to the water pump leads from the lower end of the vacuum chamber 39^a and enters a chamber in the pump structure which leads to the inlets of the impeller 35^a of the water pump, and the air conduit 26^a leads from the upper end of the vacuum chamber 39^a to the inlet chamber of the hydro-turbine pump 16^a.

The air discharge conduit 30^a leads from the discharge end of the hydro-turbine pump and opens into the water reservoir 21^a which opens to the outer atmosphere through a pipe 32^a. A float valve 22^b contained in the water reservoir 21^a controls a port through the partition 22^a and operates to admit water from the water reservoir 21^a to the vacuum chamber 39^a whenever the water in the water reservoir goes above a predetermined level.

A water pipe 54^a leads from the vacuum chamber 39^a to the hydro-turbine pump and supplies it with make up water for its operation.

A water conduit 42^a and an air conduit 44^a lead from the receiver 10^a and discharge into the vacuum chamber 39^a, and, as in the preferred form, a float valve 46^a is provided at the inlet port between the air conduit 44^a

and vacuum chamber to control the flow of water through the water conduit 42^a. A check valve 50^a operated by the float rod 47^a of the float valve mechanism operates as in the preferred form to admit air to the vacuum chamber whenever the water therein goes above a predetermined high level.

More or less variation of the exact details of construction is possible without departing from the spirit of this invention. I desire, therefore, not to limit myself to the exact form of the construction shown and described, but intend, in the following claims, to point out all of the invention disclosed herein.

I claim as new, and desire to secure by Letters Patent:

1. A water and air pumping apparatus comprising in combination a receiver for water and air, a vacuum chamber communicating with said receiver, a pump exhausting air from said vacuum chamber, whereby water and air flow from said receiver to said vacuum chamber, and a pump for discharging water from said vacuum chamber.

2. A water and air pumping apparatus comprising in combination a receiver for water and air, a vacuum chamber, a water conduit and an air conduit connecting said vacuum chamber with said receiver, a rotary pump for exhausting air from said vacuum chamber, whereby water and air flow from said receiver to said vacuum chamber, and a pump for discharging water from said vacuum chamber.

3. A water and air pumping apparatus comprising in combination a receiver for water and air, a vacuum chamber, a water conduit and a valve controlled air conduit connecting said chamber with said receiver, a rotary pump for exhausting air from said vacuum chamber, whereby water and air flow from said receiver to said vacuum chamber, and a centrifugal pump for discharging water from said vacuum chamber.

4. A water and air pumping apparatus comprising in combination a receiver for water and air, a vacuum chamber, a water conduit and a float valve controlled air conduit connecting said vacuum chamber with said receiver, a centrifugal vacuum pump for exhausting air from said vacuum chamber, whereby water and air flow from said receiver to said vacuum chamber, and a pump for discharging water from said vacuum chamber.

5. A water and air pumping apparatus comprising in combination a receiver for water and air, a vacuum chamber communicating with said receiver, a centrifugal vacuum pump for exhausting air from said vacuum chamber, whereby water and air flow from said receiver to said vacuum chamber, and a centrifugal water pump for discharging water from said vacuum chamber.

6. A water and air pumping apparatus comprising in combination a receiver for water and air, a vacuum chamber communicating with said receiver, a rotary gas pump employing water taken from said vacuum chamber for its pumping action for exhausting air from said vacuum chamber, whereby water and air flow from said receiver to said vacuum chamber, and a pump for discharging water from said vacuum chamber.
- 5 7. A water and air pumping apparatus comprising in combination a receiver for water and air, a vacuum chamber, a water conduit and a valve controlled air conduit connecting said vacuum chamber with said receiver, a rotary gas pump employing water taken from said vacuum chamber for its pumping action for exhausting air from said vacuum chamber, whereby water and air flow from said receiver to said vacuum chamber, and a centrifugal water pump for discharging water from said vacuum chamber.
- 10 8. A water and air pumping apparatus comprising in combination a receiver for water and air, a vacuum chamber communicating with said receiver, a rotary gas pump of the type employing throwing water for its pumping action for exhausting air from said vacuum chamber, a centrifugal water pump for discharging water from said vacuum chamber, and a float valve controlled passage leading from said water pump and supplying flowing water to said rotary gas pump.
- 15 9. A water and air pumping apparatus comprising a receiver for water and air, a vacuum chamber communicating with said receiver, a rotary gas pump employing water for its pumping action for exhausting air from said vacuum chamber, a water pump for discharging water from said vacuum chamber, and means for supplying said rotary gas pump with water for its pumping action from the water in the system.
- 20 10. A water and air pumping apparatus comprising in combination a receiver for water and air, a pump structure mounted thereon and containing a vacuum chamber, there being a water conduit and an air conduit leading from said receiver to said vacuum chamber, a float valve for controlling the port between the air conduit and vacuum chamber, a pump for exhausting air from said vacuum chamber, and a pump for discharging water from said vacuum chamber.
- 25 11. A water and air pumping apparatus comprising in combination a receiver for water and air, a pump structure mounted thereon and having a vacuum chamber associated therewith, a water conduit and an air conduit connecting said receiver with said vacuum chamber, a float valve in said vacuum chamber for controlling the port between the air conduit and vacuum chamber, a rotary gas pump employing water for its pumping action for exhausting air from said vacuum
- chamber, and a centrifugal pump for discharging water from said vacuum chamber.
- 30 12. A water and air pumping apparatus comprising in combination a receiver for water and air, a vacuum chamber thereabove, water and air conduits connecting said receiver with said vacuum chamber, valve mechanism for controlling the inlet port from the air conduit to the vacuum chamber whereby more or less water is caused to flow through said water conduit, a pump for exhausting air from said vacuum chamber, and discharging the same to the outer atmosphere, and a pump for discharging water from said vacuum chamber.
- 35 13. A water and air pumping apparatus comprising in combination a receiver for water and air, a pump structure mounted on said receiver, said pump structure including a gas pump employing water for its pumping action, a water pump, a vacuum chamber and a water reservoir, there being a water conduit and a valve controlled air conduit connecting said receiver with the vacuum chamber, said gas pump operating to exhaust air from the vacuum chamber and discharge the same to the outer atmosphere, and taking its water from said water reservoir and discharging it back thereinto, and said water pump operating to discharge water from said vacuum chamber.
- 40 14. Water and air pumping apparatus comprising in combination a receiver for water and air, a vacuum chamber, a water conduit and a valve controlled air conduit leading from said receiver to said vacuum chamber, there being a valve controlled air inlet for said vacuum chamber controlled by the level of water therein, a pump for exhausting air from said vacuum chamber, and a pump for discharging water from said vacuum chamber.
- 45 15. A water and air pumping apparatus comprising in combination a receiver for water and air, a vacuum chamber, a water conduit and an air conduit connecting the receiver with said vacuum chamber, a pump for exhausting air from said vacuum chamber, a pump for discharging water from said vacuum chamber, and means governed by the level of the water in the vacuum chamber for controlling the volume of water and air entering the same.
- 50 16. A water and air pumping apparatus comprising in combination a receiver for water and air, a vacuum chamber, a water conduit and an air conduit connecting the receiver with said vacuum chamber, a pump for exhausting air from said vacuum chamber, a pump for discharging water from said vacuum chamber, means governed by the level of the water in the vacuum chamber for controlling the volume of water and air entering the same, and means controlled by the level of the water in said vacuum chamber for

admitting outside air to said vacuum chamber and thereby reducing the vacuum therein.

17. A water and air pumping apparatus comprising in combination a receiver for water and air, a vacuum chamber communicating with said receiver, a pump, an air conduit leading from the upper end of said vacuum chamber to the pump, a water reservoir into which said pump discharges air and water, an air discharge passageway leading from said water reservoir, and a pump discharging water from said vacuum chamber.

18. A water and air pumping apparatus comprising in combination a receiver for water and air, a vacuum chamber communicating with said receiver, a pump, an air conduit leading from the upper end of said vacuum chamber to said pump, and having a check valve at its upper end for controlling the port from the vacuum chamber to the air conduit, a water reservoir into which said pump discharges air and water, an air discharge passageway leading from said water reservoir, and a pump discharging water from said vacuum chamber.

19. The combination with a receiver for receiving water and air from a steam heating system, of a vacuum chamber communicating with said receiver through separate water and air conduits, a rotary pump employing water for its pumping action, said pump being connected to and operating to exhaust air from said vacuum chamber by the suction and displacement action of water in the pump, and a pump connected to and operating to withdraw water from said vacuum chamber.

20. The combination with a receiver for receiving water and air from a steam heating system, of a vacuum chamber communicating therewith, a rotary pump employing water for its pumping action, said pump being connected to and operating to exhaust air from said vacuum chamber, a connection for supplying water from said vacuum chamber to said pump, and a pump acting to withdraw water from said vacuum chamber.

21. An apparatus for use in connection with the returns of a vacuum steam heating system comprising a receiver, a vacuum chamber located thereabove and communicating with the same, a pump for exhausting air from said vacuum chamber, a pump for discharging water from said vacuum chamber, and means for holding a partial vacuum in said vacuum chamber when the pumps are not in operation.

22. A water and air pumping apparatus comprising in combination a receiver for water and air, a vacuum chamber communicating with said receiver, a rotary gas pump using water for its pumping action for exhausting air from said vacuum chamber whereby water is drawn thereinto from said receiver, a water reservoir for supplying

water to said pump and for receiving water and air discharged by said pump, there being an air discharge passageway leading from said water reservoir, a water pump, the inlet of which communicates with said vacuum chamber, and means for supplying water to said water reservoir.

23. A water and air pumping apparatus comprising in combination a receiver for water and air, a vacuum chamber communicating with said receiver, a rotary pump using water for its pumping action for exhausting air from said vacuum chamber whereby water is drawn thereinto from said receiver, a water reservoir for supplying water to said pump and for receiving water and air discharged by said pump, there being an air discharge passageway leading from said water reservoir, a centrifugal water pump, the inlet of which communicates with said vacuum chamber, and there being a water passage between the water pump and water reservoir, and a float valve in said water reservoir for controlling the admission of water from said water pump to said water reservoir.
